UNITED STATES PATENT OFFICE.

GERHARD P. HELMERS, OF BALTIMORE, MARYLAND.

ALARM HAND-BAG.

1,148,773.

Specification of Letters Patent. Patented Aug. 3, 1915.

Application filed January 7, 1914. Serial No. 810,766.

To all whom it may concern:

Be it known that I, GERHARD P. HELMERS, a citizen of the United States, residing at Baltimore city, State of Maryland, have invented certain new and useful Improvements in Alarm Hand-Bags, of which the following is a specification.

This invention is in the nature of an alarm especially adapted to be attached to a satchel or hand bag such as carried by ladies, but applicable to all forms of receptacles which are provided with hinged jaws or doors to be opened to afford access to the interior.

15 The prime object of the invention is to provide means to prevent the surreptitious opening of a receptacle of the character specified without giving an audible alarm, and to provide means whereby the alarm mechanism may be rendered inoperative when desired.

With this object in view the invention consists of the improved construction, arrangement, and combination of the component parts of mechanism of the character specified, which will be hereinafter fully described and afterward specifically claimed.

In order that the construction and operation thereof may be readily comprehended, the invention will now be specifically described, in connection with the accompanying drawings, which illustrate an approved embodiment of the invention adapted to a hand bag or satchel, in which drawings—

35 Figure 1 represents a perspective view of a hand bag equipped with the invention, parts of the bag being broken away, Fig. 2, a detail view of the switch for rendering the alarm and shocking mechanism inoperative, Fig. 3, a fragmentary detail view of the hinge, with the switch connected thereto, and Fig. 4, a diagrammatic view of the battery, alarm, shocking bars and electric connections.

40 45 Like reference characters mark the same parts wherever they occur in a plurality of figures of the drawings.

Referring specifically to the drawings 6 indicates a bag or a satchel or the like, provided with hinged mouth bars 7, 8, connected by the usual pintles 9 and provided with the usual handle 10. A battery 11 of any suitable type is located suitably in the bag, as shown in dotted lines in Fig. 1 and indicated diagrammatically in Fig. 4, from one pole of which extends a wire 12 to an

alarm bell 13 from whence extends a wire 14 to a plate 15. Adjacent to the plate 15 is a similar plate 16 from which extends a wire 17 to a bar 18 on top of the handle 10 which is connected by a wire 19 to a bar 20 under the handle. From the opposite end of the bar 20 extends a wire 21 to the other pole of the battery, a switch 22 being inserted in this wire to break the circuit when desired.

The bell 13 shown in Fig. 4, is protected by inclosing it in a perforated box 23, shown in Fig. 1.

When the mouth of the bag or satchel is closed, the circuit is broken, but when an attempt is made to open the satchel, a switch or contact bar 24, rigidly secured to one of the mouth bars and projecting down below the pintle, passes over upon the plates 15 and 16 and closes the electric circuit through said plates, thus sounding the alarm bell 13. This alarm will sound and warn the owner of the bag of an attempt to open it whether the bag is carried, or not, the current passing from bar 18 to bar 20 through parts of the hand, so that due warning will be given whether the alarm by the bell is heard or not.

While the construction and arrangement of the component parts of the invention have been specifically described, it will be obvious that slight changes and variations may be made therein, without departing from the spirit and scope of the invention.

Having thus fully described the invention, what is claimed as new and desired to be secured by Letters Patent of the United States is:—

1. A portable closable bag provided with hinged mouth bars, an alarm and a battery in a normally open circuit inclosed in said bag, and means connected to one of said mouth bars and operated thereby for closing said circuit and retaining it closed while said mouth bars are separated and during their entire opening movement, and an additional means within the bag for breaking the circuit to prevent the ringing of the alarm when the bag is opened.

2. A portable closable bag provided with hinged mouth bars, an alarm and battery in a normally open circuit having contact plates spaced apart secured upon the interior of said bag adjacent the hinge of the mouth bars, an extension attached to one of said mouth bars and adapted to be operated

thereby to engage said contact plates when said mouth bars are separated, and a switch in said circuit for controlling the ringing of the alarm.

5. 3. A portable closable bag provided with hinged mouth bars and a handle, an alarm in said bag, separated plates fixed to said handle, means in said bag connected in a normally open circuit with said alarm and 10 separated plates, and means connected to

one of said mouth bars for closing said circuit and retaining it closed when said mouth bars are separated.

In testimony whereof I affix my signature in presence of two witnesses.

GERHARD P. HELMERS.
